UNITED STATES PATENT OFFICE.

JOHN W. HANCOCK, OF DENVER, COLORADO.

DESIGN FOR AN ELECTRIC-LIGHT FIXTURE.

Application filed March 23, 1923. Serial No. 5,575. Term of patent 3½ years.

To all whom it may concern:

Be it known that I, JOHN W. HANCOCK, a citizen of the United States, residing at Denver, in the county of Denver and State of Colorado, have invented a new, original, and ornamental Design for an Electric-Light Fixture, of which the following is a specification, reference being had to the accompanying drawing, forming part thereof.

In this drawing:

Figure 1 is a perspective, and Fig. 2 a side elevation of a fixture embodying my invention.

I claim:

The ornamental design for an electric light fixture, as shown.

JOHN W. HANCOCK.
